(57) **CLAIM**

The ornamental design for a lamp, as shown and described.

DESCRIPTION

Figure 1.1 is a top perspective view of my new design for a lamp

Figure 1.2 is a front side elevation view of Figure 1.1

Figure 1.3 is a back side elevation view of Figure 1.1

Figure 1.4 is a left side elevation view of Figure 1.1

Figure 1.5 is a right side elevation view of Figure 1.1

Figure 1.6 is a top side plan view of Figure 1.1

Figure 1.7 is a bottom side plan view of Figure 1.1

The features shown in broken lines in the drawing depict environmental subject matter only and form no part of the claimed design
